METHOD OF AND APPARATUS FOR THE ROLLING OF METAL STRIPS AND SHEETS

Application filed June 15, 1928. Serial No. 285,622.

This invention relates to an improved method and apparatus for use in the manufacture of metal strips and sheets, particularly sheets and strips of steel, whereby the sheets or strips may be rolled to a relatively thin gauge with one heating. The principal object of the invention is to provide improved apparatus for doubling the partially reduced and elongated hot metal sheet upon itself to 10 form a "pack" which is subjected to further action by reducing rolls for forming a plurality of superimposed sheets of finer gauge than can be produced by the rolling of a single sheet. A further object of the invention is to provide an improved method by 15 which strips and sheets can be rolled with a single heating of the metal by a process which involves the automatic doubling of the sheet upon itself when partially reduced and also 20 the edge rolling of the sheet during its travel so that the finished sheets are of relatively fine gauge and of definite width. A further object of the invention is to provide improved apparatus comprising means for engaging the partially reduced and elongated 25 hot sheet during its travel through the mill whereby the forward end of the hot sheet is automatically held and elevated to permit the body portion of the sheet to travel beneath 30 the elevated end, thereby doubling the sheet upon itself and forming a plurality of layers 35 of hot metal which are further reduced to a finished gauge by the operation of the finishing rolls. Other objects relate to various features of construction and arrangement which will appear more fully hereinafter.

The nature of the invention will be understood from the following specification taken 40 with the accompanying drawings in which one form of apparatus embodying the invention is illustrated. In the drawings,—

Figure 1 shows a somewhat diagrammatic top plan view of a rolling mill embodying 45 the features of the present invention;

Fig. 2 shows a diagrammatic side elevation of the apparatus illustrated in Fig. 1;

Fig. 3 shows an enlarged diagrammatic side elevation of the intermediate portion of 50 the apparatus illustrated in Fig. 1 by which

the hot metal sheet, partially reduced, is doubled upon itself;

Fig. 4 shows a side elevation of the apparatus by which the forward end of the traveling sheet is gripped and elevated;

Fig. 5 shows a vertical section on the line 5-5 of Fig. 6, illustrating the construction of one of the gripping arms and its gripping dog; and

Fig. 6 shows an end elevation of the gripping apparatus by which the end of the sheet is gripped and elevated, the view being taken looking toward the right as viewed in Fig. 4.

In carrying out the manufacture of metal strips or sheets with the use of the apparatus illustrated in the accompanying drawings, the hot ingots are first formed into elongated slabs preferably several feet long, two inches or more in thickness and about four inches or more in width. These elongated slabs are 55 heated in a suitable furnace 10 to the temperature required for the subsequent reducing operations, preferably a temperature about 2300 degrees Fahrenheit. These hot metal slabs are discharged from the furnace 10 one at a time, into the guide channel 11 of the mill where they are fed by feeding rollers 13 between the reducing rolls 12 which constitute the first set of a series of roughing rolls by which the hot slab is partially reduced and elongated. The rolls 12 engage the flat slab on its edges for the purpose of producing a uniform width from end to end, and after passing through these rolls the slab is 60 manually tilted onto its flat side before it passes into the second set of rolls 14 by which its gauge is reduced. The slab is then manually or automatically set up on its edge again and passed through another set of rolls 15. After passing through the rolls 15, 65 the slab is returned to its flat side on the feeding rolls of the guide channel 11 before passing through the reducing rolls 16. The edge of the partially reduced slab is then engaged by the edge rollers 17 which rotate 70 about vertical axes. As the partially reduced and elongated bar emerges from the edge rollers 17 it passes between the horizontal rollers 18 which constitute the final reducing rollers of the roughing set. The various 75

100

reducing or horizontal rollers 12, 14, 15, 16 and 18 are driven by gearing 19 and the driving shaft of each gearing set 19 is connected by bevel gears 20 with a common driving shaft 21 arranged to be actuated by a reducing gear set 22 leading from an electric motor 23. The edge rollers 17 have vertical shafts connected to a driving shaft 24 which is driven by an electric motor 25.

10 As the partially reduced and greatly elongated hot metal bar emerges from the final set of roughing rolls 18, it is in readiness to be doubled upon itself by the apparatus of the present invention. If the operation is 15 being carried on at a relatively high temperature, such as that suggested above, there is preferably applied to the top surface of the hot metal strip or bar, before it is doubled, a suitable separating agent for preventing the 20 superimposed hot metal layers from adhering to each other in the rolling which takes place following the doubling operation. This separating agent may preferably be sodium carbonate applied according to the improved 25 method described and claimed in the co-pending application of Ralph H. Norton, Serial No. 285,621, filed June 15, 1928.

This separating agent is applied to the top surface of the traveling elongated bar 26 from a suitable sifting box or shaker 27 which is located over the guide channel 11 of the mill immediately following the rolls 18. Immediately after passing the sifting box 27, the forward end of the traveling bar 26 is 30 automatically engaged by a pair of gripping arms 30 which are pivotally mounted to swing upwardly and away from the rolls 18 so that, as the forward end of the traveling bar is elevated, in the manner illustrated in Fig. 3, the trailing portion of the elongated bar 26 is automatically fed beneath the arms 30 thereby causing the elongated flat bar to be doubled upon itself as shown in Fig. 3. The apparatus by which the forward end of the traveling elongated bar is gripped and elevated has the form shown particularly in Figs. 4, 5, and 6. This apparatus is carried by a pair of auxiliary frames 31 detachably secured to the sides of the guide frame or channel 11 by means of bolts 32 detachably engaging sockets 33. The frames 31 have journaled therein a transverse shaft 34 provided at one end with a crank 35 and at the other end with a fixed collar 36 so that the shaft is restrained against longitudinal movement. The crank handle 35 has a depending arm 37 which is normally maintained in engagement with a stop pin 38 by means of a coil spring 39 connected to the lower end of the arm 37 and to a pin 40 secured to the adjacent frame 31. Between the frames 31, the shaft 34 has journaled thereon the two gripping arms 30 each of which has an upward extension 30^a secured to a transverse rod 42. The rod 42 projects laterally over

one of the auxiliary frames 31 adjacent the handle 35 and this projecting portion of the rod carries a pivotally mounted pawl 43 which is actuated by a coil spring 44, mounted on the rod, to engage the ratchet teeth 45 of the sector 46 which forms the upper part of one of the side frames 31. The lower end of each gripping arm 30 is provided with a hooked jaw 48 having the form illustrated particularly in Fig. 5. This jaw has a relatively narrow recess 49 adapted to be engaged by the end of the oncoming bar of metal and the mouth of the jaw is provided with an upturned flange 50 for the purpose of guiding the metal into the recess 49. As the forward end of the traveling bar engages the recesses 49 in the two gripping arms 30, which are located in the same plane, these arms are forced upwardly and toward the right as viewed in Figs. 3 and 5, and this motion causes the 75 end of the bar to be automatically gripped by the jaws 48 due to the action of gripping dogs 51 which extend downwardly from the shaft 34 and which are provided at their upper ends with split bearing members 52 arranged to be journaled on the reduced and eccentrically located portions 53 of the shaft 34. These eccentric portions are located adjacent to the arms 30 and the jaws 48 are elongated laterally from the lower ends of the 80 arms 30, as shown in Fig. 6, so that the gripping dogs 51 are permitted to engage apertures 54 which are formed in the top walls of the jaws 48. As the arms 30 are swung upwardly about the shaft 34 by the action of the 85 moving elongated bar of hot metal, the jaws 48 move in paths which are eccentric with respect to the pivotal supports of the gripping dogs 51 so that these dogs are forced downwardly through the openings 54 and are 90 caused to grip the edge of the sheet and retain it securely in position within the jaws. When the arms 30 reach a limiting position which is determined principally by the weight of the 95 bar and its speed of travel, it is retained in that position by the engagement of the pawl 43 with one of the ratchet teeth 45 so that the arms 30 then hold the end of the elongated bar 26 in an elevated position, as shown in Fig. 3, while the trailing portion of the bar 100 travels beneath the arms 30 and the bar is thereby doubled upon itself. When the trailing end of the bar reaches a position adjacent to the location of the arms 30, the operator standing at the side of the mill releases the forward end of the bar from the 105 jaws 48 by turning the crank handle 35 toward the left as viewed in Fig. 4, thereby rotating the shaft 34 and causing the eccentric portions 53 of the shaft to elevate the gripping dogs 51 out of engagement with the sheet. The doubled bar then advances bodily 110 on the underlying rollers of the guide channel 11 and engages other rollers by which the superimposed layers of the bar are flattened 115

120

125

130

upon each other. As the double bar 26 advances over the underlying rollers 55, the bent extremity 26^a thereof engages a pair of rolls 56 which partially compress the bent

5 end of the bar so as to cause it to assume the form indicated by dotted lines at 57. This bent portion, of reduced vertical dimension, then engages another set of rolls 58 which further compress the bent end to cause it to

10 assume the condition shown at 59 in Fig. 3. This part 59 then engages a pair of closely spaced rolls 60 which effect the final operation of flattening the upper section 26^b of the bar upon the lower section 26^c. These rolls

15 56, 58 and 60, which form a gradually diminishing passage for the traveling sheet, are actuated by a common driving mechanism 61 driven by an electric motor 62, as shown in Fig. 1. Upon emerging from the converging

20 series of rolls by which the bar is flattened upon itself, the bar is in readiness for the final reducing operation, preliminary to which it is passed between a pair of edging rolls 65 which are mounted on vertical axes and which

25 are driven by a common driving shaft 66 actuated by an electric motor 67. The forward end of the doubled bar, upon emerging from the space between the edging rolls 65, is engaged by the first pair of reducing rolls

30 68 and it then passes successively through a number of similar sets of reducing rolls 69, four of which sets are illustrated in the accompanying drawings. The reducing rolls 68 and 69 are actuated by suitable gearing in

35 the gear boxes 70 and the mechanism of each gear box is in turn driven by an electric motor 71. These motors 71 are preferably driven at different speeds to compensate for the gradual reduction in thickness of the "pack"

40 made up of the superimposed layers of the metal bar. During the progress of the bar through the finishing rolls 68 and 69, it is important to keep the top layer 26^b in exact alignment with the lower layer 26^c and for

45 this purpose each of the pairs of reducing rolls 69 is preceded by vertical guiding rollers 73 each pair of which is actuated by a common driving shaft 74 having a driving connection by a chain 75 with the shaft 76

50 by which the motor 71 of the next preceding set of reducing rolls is connected to its gear box. In this way each set of guiding rolls 73 is driven with a speed corresponding with the speed of the reducing rolls of the next

55 preceding set by which the elongated bar is still engaged at the time that the forward end of the bar is first contacted by the guiding rollers of that particular set. The guiding rollers 73 and parts associated therewith

60 may preferably be of the form described and claimed in the co-pending application of Ralph H. Norton, Serial No. 285,623, filed June 15, 1928.

65 It will be apparent that by the means described in the foregoing specification it is

possible to effect the doubling of a bar of hot metal after the partial reduction thereof for the purpose of effecting a further reduction to a relatively thin or sheet gauge and of definite width without the employment of complicated mechanism for effecting the doubling operation. Although one form of the invention has been shown and described by way of illustration, it will be understood that it may be constructed in various other forms within the scope of the appended claims. The folding device illustrated and described herein is claimed in our co-pending divisional application Serial No. 386,303, filed August 16, 1929.

70 75 80

We claim:

1. The method of manufacturing metal sheets or strips which consists in reducing a slab to form an elongated bar, then holding the forward end of said bar stationary while continuing to advance the trailing portion thereof to thereby double said bar upon itself, and then rolling and reducing the doubled bar to thin gauges.

2. The method of manufacturing metal sheets or strips which consists in reducing a slab to form an elongated bar, then holding the forward end of said bar stationary while continuing to advance the trailing portion thereof to thereby double said bar upon itself, 85 and then releasing said doubled bar and advancing it bodily between rolls adapted to flatten the advancing doubled end thereof.

3. The method of manufacturing metal sheets or strips which consists in reducing a slab to form an elongated bar, then holding the forward end of said bar stationary while continuing to advance the trailing portion thereof to thereby double said bar upon itself, then releasing said bar and advancing 100 it bodily between rolls adapted to flatten the advancing doubled end thereof, and then running the doubled bar through finishing rolls.

4. The method of manufacturing metal sheets or strips which consists in reducing a slab to form an elongated and partially reduced bar, then holding and elevating the forward end of said partially reduced bar while continuing to advance the trailing portion thereof beyond said end, then releasing 115 said end of said bar and advancing said bar through a plurality of sets of rolls having a gradually diminishing spaced relation, and then further reducing the superimposed layers of said bar to thin gauges.

5. The combination in apparatus for the manufacture of metal sheets and strips, of means for rolling a slab to form a partially reduced and elongated bar, means for engaging and holding the forward end of said 125 elongated bar while permitting the remaining portion thereof to be advanced beyond said holding means to effect the doubling of said elongated bar, and means for reducing the superimposed layers of said doubled bar.

120

130

6. The combination in apparatus for the manufacture of metal sheets and strips, of means for partially reducing a hot slab to form an elongated flattened metal bar of substantially uniform width, means for holding the forward end of said elongated bar while permitting the trailing portion thereof to advance beyond said holding means to double said sheet, means for flattening the doubled end of said bar, and means for thereafter reducing the superimposed layers of said bar. 7. The combination in apparatus for the manufacture of metal sheets and strips, of means for reducing a hot metal slab to form an elongated bar, means for automatically engaging and elevating the forward end of said bar while permitting the trailing portion thereof to advance beneath said holding means, means for flattening the doubled end of said bar, and means for further reducing the superimposed layers of said doubled bar. 8. The combination in apparatus for the manufacture of metal sheets and strips, of means for reducing and feeding a hot metal slab to form an elongated partially reduced bar, means for automatically engaging and elevating the forward end of said elongated bar and holding said end stationary while permitting the trailing portion thereof to be fed forwardly beneath said holding means, and means for further reducing the superimposed layers of the bar which is doubled by the operation of said last named means. 9. The combination in apparatus for the manufacture of metal sheets and strips, of means for reducing and feeding a hot metal slab to form an elongated partially reduced bar, means for automatically engaging and elevating the forward end of said elongated bar and holding said end stationary while permitting the trailing portion thereof to be fed forwardly beneath said holding means, a plurality of sets of rolls arranged with the rolls of one set having a lesser spaced relation than the rolls of the next preceding set to effect the flattening of the doubled end of said bar, and means operative thereafter for reducing the superimposed layers of said doubled bar. 10. The combination in apparatus for the manufacture of metal sheets and strips, of means for feeding an elongated metal bar, means for engaging and elevating the forward end of said bar to permit the trailing portion thereof to pass beneath said elevating means, and means operative thereafter for flattening the doubled end of the bar and reducing the superimposed layers thereof. 11. The combination in apparatus for the manufacture of metal sheets and strips, of means for feeding an elongated metal bar, a pivotally mounted arm having means adapted to engage and automatically grip the forward end of said bar during its travel, and means for flattening and reducing the doubled bar after the forward end thereof has been released from said arm. In witness whereof, we have subscribed our names.
